UNITED STATES PATENT OFFICE

GEORGE B. TAYLOR, OF HAVERFORD TOWNSHIP, DELAWARE COUNTY, PENNSYLVANIA

RAILROAD TRACK CONSTRUCTION

Application filed March 14, 1931. Serial No. 522,651.

This invention relates to new and useful improvements in railway track construction and more particularly to means for securing the track rails to the track bed.

One object of the invention is to provide a railway track construction which is readily adaptable to both standard steam and electric railways, and also street railways wherein the upper surface of the rails is substantially level with the surface of the street.

Another object of the invention is to provide a railway construction having novel means for securing the track rails to the track bed.

Another object of the invention is to provide a railway track construction having novel means for releasably securing the track rails to the track bed, said means being positioned to permit lateral gauge adjustment of the rails subsequent to the laying thereof.

Another object of the invention is to provide a railway track construction having novel means for insulating the track rails from the track bed.

A further object of the invention is to provide a railway track construction having means for locking the track securing elements thereby preventing the track rails from becoming loosened.

A further object of the invention is to provide a railway track construction having means for securing the rails to the rail bed in such manner as to prevent longitudinal movement of the rail with respect to the rail supports and commonly known as "creeping".

The invention further resides in certain structural details set forth hereinafter and shown in the accompanying drawings, in which:

Figure 1 is a fragmentary sectional view showing the construction used in laying railway tracks embodying my invention;

Fig. 2 is a side elevation showing the construction of the anchor members used to secure the track rails to the track bed;

Fig. 3 is a side view showing the construction of the insulating wedge and locking device to be used in conjunction with the anchor members for securing track rails to the track bed;

Fig. 4 is an end elevation of the wedge member shown in Fig. 3;

Fig. 5 is a side elevation of the member normally disposed intermediate a wedge and the track rail and engaging the base thereof;

Fig. 6 is an end elevation showing the engaging member shown in Fig. 5;

Fig. 7 is a fragmentary sectional view showing the construction of a railway track adapted for street railways, wherein the upper surface of the track rail is substantially level with the surface of the street;

Fig. 8 is a side elevation of the wedge member having the engaging member formed integrally therewith;

Fig. 9 is an end elevation of the disclosure in Fig. 8; and

Fig. 10 is a fragmentary plan view of the track shown in Fig. 1.

Referring to the drawings, the anchor members 1 are embedded in a concrete foundation 2, preferably prior to the positioning of the track rails, the said anchor members 1 in the present instance having their end portions formed to converge toward the track rail as shown in Fig. 1 of the drawings. In the present instance the plane of the inner face of the upper converging portion of the anchors 1 is formed at an angle with respect to both the longitudinal axis of the track rail 3 and the horizontal surface of the track bed. The said inner face of the converging portion of each of a pair of oppositely disposed anchor members 1 is disposed at an opposite equal angle to that of the other face of the opposite anchor element, thus permitting the retaining members to be driven from opposite sides of each of a pair of oppositely disposed anchors.

Subsequent to the embedding of the anchor members 1, a continuous member 4 of wood or other suitable material is disposed intermediate the anchor members 1 and parallel with respect to the longitudinal axis of the track rail 3, the upper surface of the concrete track bed beneath member 4 having previously been formed by suitable means, to a reasonably true surface for the placement of said member 4. The track rails 3 are then positioned on the member 4 intermediate the

oppositely disposed or staggered anchor elements 1.

For the purpose of securing the track rails to the track bed, I provide engaging elements 6 having a cutout portion 7 formed therein as shown in Fig. 6 and adapted to engage the outer edges of the track rail 3 when disposed adjacent each of the anchor members 1. A second cutout portion 8 is formed in the outer face of the engaging member 6, the purpose 10 of which will be set forth hereinafter.

For the purpose of rigidly securing the engaging members 6 to the base of the track rail, thereby holding it securely in position, I provide suitable wedge members 9 shown in 15 Figs. 3 and 4 of the drawings, the said wedge members 9 being disposed intermediate the inner face of the upper portion of the anchor members 1 and the upper face of the engaging members 6. In the present instance the edges of the lower face of the wedge members 9, normally abutting the upper face of the engaging members 6 are beveled as shown at 20 10 in Figs. 3 and 4 of the drawings, to permit that portion of the wedge to normally reside in the cutout portion 8 formed in the upper face of the engaging members 6 when the said wedge members 9 are entirely in position, and thus afford a substantial means of 25 preventing the wedge members 9 from becoming separated from the engaging members 6.

As a means for further securing the wedge members in position when the said members have been finally secured I provide a strip 35 of steel 11 which is normally disposed intermediate the upper face of the wedge 9 and the inner face of the anchor member 1; and to lock the wedge securely in position it is merely necessary to form one end of the strip 40 11 over the side of the anchor member 1, the other end of the said strip 11 being bent over the end of the wedge 9, as shown in Fig. 3.

In the present construction, I prefer to embed the anchor members 1 in the concrete foundation prior to the positioning of the track rail 3 and it is obvious that the anchor members 1 may be of any suitable form providing that the upper inner face thereof 50 is disposed at an angle with respect to the longitudinal axis of the track rails and also at an angle with respect to the surface of the track bed. The use of the wedges disposed as they are in the present case, permit of the 55 lateral adjustment of the rail to the desired gauge, by first driving one or the other of the opposing wedges.

In the case of open track on railways where 60 it becomes necessary to provide for electric circuits which require the insulation of the rail from the supporting structure and the anchor members, the wedge members 9 are composed of insulating material, such as 65 wood, hard rubber or other suitable insulat-

ing material. In such cases the supporting member 4 is likewise wood or other suitable insulating material and it is even desirable to place a layer of insulating mastic, designated as 12 in Fig. 1, on the upper surface 70 of the concrete and extending from the edge of the supporting member 4 to the outer line of the anchor members 1 disposed adjacent each side of the rail; the combination of the insulating mastic, the supporting 75 member 4 and the wedge portions 9 effectively insulating the rail from the anchor members 1 and the concrete base.

In the case of track construction shown in Fig. 7 and particularly adapted for use in 80 street railways, wherein the surface of the street pavement is normally flush with the level of the track rails, and wherein the insulation of the track rails from the anchor members and the concrete base is not required, 85 it is preferable to form the wedge member and the engaging member of metal and as an integral unit designated as 9a and shown in Figs. 8 and 9 of the drawings. In this type of construction the track rails are 90 secured to the road foundation in a manner similar to that set forth above and in addition a further application of concrete 14 (see Fig. 7) is disposed about the upper portion 95 of the anchor members and about the wedges to a suitable height thereabove, the customary road surfacing material 15 being subsequently placed thereon to a height substantially level with the upper surface of the 100 track rail.

It will be apparent that the unit wedge and engaging member 9a may be used in the construction of open track work similar to that shown in Fig. 1 and may be composed either of insulating or non-insulating material as is necessary under the circumstances. Also it will be apparent that certain further changes in details of the construction may be made without departing from the spirit of the 105 invention.

I claim:

1. In a railway track construction, means for securing track rails to a track bed comprising a plurality of anchor members each having the upper inner face thereof disposed at an angle to the longitudinal axis of the track rail and at an angle to the plane of the surface of the road bed, and wedge members disposed intermediate and abutting the inner face of the anchor members and the base of the track rail for holding the said rail firmly in position. 115

2. In a railway track construction, means for securing the track rails to a track bed comprising a plurality of anchor members each having the upper inner face thereof disposed in a manner such that the intersection of the plane of the said face with the longitudinal axis of the track rail forms an acute angle, and wedge members disposed 120 125 130

intermediate and abutting said face and the base of the track rail for holding the said rail securely in position.

3. In a railway track construction, means for securing the track rails to the track bed comprising a plurality of anchor members each having the upper inner face thereof disposed at an angle to the longitudinal axis of the track rail, engaging members for gripping the edges of the base of the track rail, and wedge members disposed intermediate the said inner face of the anchor members and the engaging members for holding the track rail securely in position.

4. In a railway track construction, means for securing the track rails to the track bed comprising a plurality of anchor members each having the upper face thereof disposed at an angle to the longitudinal axis of the track rail and to the plane of the surface of the track bed, engaging members for gripping the edge of the base of the track, and wedge members disposed intermediate the said inner face of the anchor members and the engaging members for holding the track rails securely in position.

5. In a railway track construction, means for securing the track rails to the track bed comprising a plurality of anchor members disposed adjacent each side of the rail and each having the upper inner face thereof disposed in such a manner that the intersection of the plane of said inner face with the longitudinal axis of the rail forms an acute angle, engaging members for gripping the edge of the base of the track, and wedge members disposed intermediate the inner face of the anchor members and the engaging members for holding the track rails securely in position.

6. In a railway track construction, means for securing track rails to a track bed comprising a plurality of anchor members, each having the upper inner face thereof disposed at an angle to the longitudinal axis of the track rails, wedge members disposed intermediate the said inner face of the anchor members and the base of the track rail for holding said track rail securely in position, and engaging strips for locking the said wedge members in the holding position.

7. In a railway track construction, means for securing the track rails to a track bed comprising a plurality of anchor members each having the upper inner face thereof disposed in a manner such that the intersection of the plane of the said face with the longitudinal axis of the track rail forms an acute angle, wedge members disposed intermediate and abutting said face and the base of the track rail for holding the said rail securely in position, and means for locking the said wedge members in the holding position.

8. In a railway track construction, means for securing the track rails to the track bed

comprising a plurality of anchor members disposed adjacent each side of the rail and each having the upper inner face thereof disposed in such a manner that the intersection of the plane of said inner face with the longitudinal axis of the rail forms an acute angle, engaging members for gripping the edge of the base of the track, wedge members disposed intermediate the inner face of the anchor members and the engaging members for holding the track rails securely in position, and means for locking the said wedge members in the holding position.

9. In a railway track construction, means for securing the track rails to the track bed comprising a plurality of anchor members embedded in said track bed and disposed in spaced relation adjacent each side of the track rail, the said anchor members having their upper ends converging toward said rail and the inner face of said converging portion disposed at an angle to the longitudinal axis of the rail, engaging members for gripping the edge of the base of the track, and wedge members disposed intermediate the inner face of the anchor members and the engaging members for holding the track rail securely in position.

10. In a railway track construction, means for securing the track rails to the track bed comprising a plurality of anchor members embedded in said track bed and disposed in spaced relation adjacent each side of the track rail, the said anchor members each having the upper end thereof converging toward the track rail and the inner face of said converging portion disposed at an angle to the longitudinal axis of the said rail, engaging members for gripping the edge of the base of the rail, and disposed at the base of the rail opposite the anchor members, and wedge members intermediate the inner face of the anchor members and the engaging members for holding the track rails securely in position, the said wedge members being composed of insulating material.

11. In a railway track construction, means for securing the track rails to the track bed comprising a plurality of anchor members embedded in said track bed and disposed in spaced relation adjacent each side of the track rail, the said anchor members having their upper ends converging toward said rail and the inner face of said converging portion disposed at an angle to the longitudinal axis of the rail, engaging members for gripping the edge of the base of the track, wedge members disposed intermediate the inner face of the anchor members and the engaging members for holding the track rail securely in position, and means for locking the wedge in the holding position.

12. In a railway track construction, means for securing the track rails to the track bed comprising a plurality of anchor members

- embedded in said track bed and disposed in spaced relation adjacent each side of the track rail, the said anchor members each having the upper end thereof converging toward
- 5 the track rail and the inner face of said converging portion disposed at an angle to the longitudinal axis of the said rail, engaging members for gripping the edge of the base of the rail and disposed at the base of the
- 10 rail opposite the anchor members, and wedge members intermediate the inner face of the anchor members and the engaging members for holding the track rails securely in position, the said wedge members being composed
- 15 of insulating material, and means for locking the wedge in the holding position.

GEORGE B. TAYLOR.
